[57] CLAIM

We claim the ornamental design for the wine rack, as shown and described.

DESCRIPTION

FIG. 1 is a front elevation view of a wine rack showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a top perspective view thereof.

No claim is made to color, shading, or any pattern in the design.
